UNITED STATES PATENT OFFICE

DAVID P. ANDERSON, JR., OF PITTSBURGH, AND EARL C. MILLER, OF MCKEESPORT, PENNSYLVANIA, ASSIGNORS TO HARRY W. SCHUETZ, OF PITTSBURGH, PENNSYLVANIA

BLAST FURNACE CHARGING APPARATUS

Application filed November 18, 1930. Serial No. 496,535.

This invention relates to improvements in blast furnace charging and distributing mechanism and it is among the objects thereof to provide charging and distributing equipment for blast furnaces which shall produce a more gas-tight furnace top and which shall greatly improve the distributing of stock in the furnace.

Blast furnace bells now in use range from 10 twelve to fifteen feet in diameter and weigh from twelve to twenty-two tons, requiring expensive and powerful machinery to manipulate them in their stock charging movements. Furthermore, the large bells are 15 subject to warping and do not seat very accurately with the result that gas escapes from the top of the blast furnace. Then too, occasionally more stock accumulates on one side of the bell than on the other which causes 20 the large bell to tilt when lowered, producing non-uniform distribution of the material and improper seating when closed.

In accordance with the present invention, 25 a distributor is utilized in conjunction with the bell which permits reducing the size of the bell to substantially one-half of that now in use, thereby eliminating to a great extent the difficulties referred to and, in addition, the arrangement of the distributor and bell 30 is such that it produces substantially uniform distribution of the stock, which is an improvement in blast furnace operation.

These and other objects of the invention will become more apparent from a consideration of the accompanying drawings in which like reference characters designate like parts and in which Figure 1 is a vertical sectional elevational view of an improved furnace top embodying the principles of this invention; 40 Figure 2 is a section taken along the line II-II, Figure 1; and Figures 3 and 4 are top plan and side views, respectively, of a deflector plate and the manner of its mounting for the purpose to be hereinafter explained.

In the drawings, 1 designates the top of the blast furnace structure on which is supported the frame work generally designated at 2, which carries a receiving hopper 3 and a charging hopper 4, the bottom portions of

which terminate in the shape of inverted truncated cones 5 and 6, respectively. The charging hopper 4 is provided with a cover 7, and the receiving hopper and the charging hopper are provided with bells 8 and 9, respectively, which seat against the bottoms of the hoppers to support material charged therein and to constitute seals against the escape of gas from the interior of the blast furnace.

Material is delivered to the receiving hopper 3 by skip cars 10 which operate on inclined tracks 11 in a well known manner, and when the receiving hopper is fully charged, the bell 8 is lowered to charge the 65 hopper 4 while maintaining the lowered bell 9 in its closed position.

The top of the blast furnace is provided with the usual gas outlet 12 and the valves are operated through well known mechanism generally designated at 13.

Below the charging hopper 4 and in vertically spaced relation therewith is a distributor 15 of conical shape, the outer face 16 of which forms in effect an extension of 75 the base of the bell 9 for the purpose of distributing the stock to the extreme outer portion of the furnace chamber in the same manner as the stock would be distributed were the distributor a portion of the bell. 80 Distributor 15 is in vertically spaced relation with and secured to a supporting ring 17 by a plurality of supporting brackets 18, there being four such brackets as shown in Figure 2 of the drawings. Above the supporting ring 17 is an annular cover 19 provided with inspection doors 20 which doors are in alignment with the brackets 18 of the distributor.

A plurality of deflector plates 21 are 90 fastened to the brackets 18 as shown in Figures 3 and 4 of the drawings, the deflector plates being provided with hooks 22 at one end which engage a cast lug 23 on the supporting brackets 18 and the other end of the 95 deflector plates are provided with upturned portions 24 adapted to fit between keys 26 mounted in slots 25 in the supporting ring 17. The keys 26 prevent lateral and vertical displacement of the plates 21 and are 100

readily removed to permit removal of the plates.

By constructing and maintaining the deflector plates 21 as herein described they may be readily removed through the inspection doors 20 and replaced by deflector plates of different widths, either greater or less width depending upon the amount of stock desired to be diverted by the plates toward the center of the blast furnace.

In the operation of the blast furnace embodying the aforementioned improvements, the receiving hopper 3 is charged with stock by the skip cars 10 and the upper bell is lowered through its operating mechanism 13 to empty the charge into the charging hopper 4 which has its bell 9 in closed position.

The bell 8 of the receiving hopper 3 is then closed and the bell 9 opened to permit 20 the charge to drop on the distributor 15 and a portion of it to be diverted by the deflector plates 21 whereby stock is distributed toward the outer and central portions of the furnace to produce a substantially uniform 25 stock level.

The bell 9 of the charging hopper is then closed, and the hopper 4 is again charged by the receiving hopper in the manner explained, and by alternately operating the 30 bells 8 and 9, having one closed while the other is opened, gas cannot escape through the hoppers but passes out through the gas outlet 12.

It will be noted that on account of the relatively small diameter of the bell, there will be very little interference with the gas flow so that the gas will pass out of the furnace 35 at substantially uniform velocity which reduces the passage of dirt from the furnace chamber.

If, during the charging of a furnace, it is desired to change the degree of distribution of the stock toward the center of the furnace chamber, the deflector plates 21 may be replaced by other deflector plates by simply shutting off the blast for a short period and removing the plates through the windows 20 in the manner explained. By providing 40 for the interchangeable deflector plates, any degree of stock distribution, that is, any desired manner of distributing the stock along the cross section of the furnace chamber, can be produced without interfering with the operation of the furnace to any great 45 extent.

It is evident from the foregoing description of the invention that the constructions of the distributor and the bell of the charging hopper permit the use of a movable bell of relatively small diameter which possesses the distributing effect of a larger bell by use of the distributor 15 which functions as an extension of the sloping side of the bell and in addition provides for diversion of part of 50 the stock to the center of the furnace.

Although one embodiment of the invention has been herein illustrated and described, it will be obvious to those skilled in the art that changes in the details of construction may be made without departing 70 from the principles herein set forth.

We claim:

1. A blast furnace having in combination a charging hopper, a relatively small bell closing upward against the lower end of said hopper and a distributor suspended in fixed position below said bell and having a conical face constituting an annular enlargement of the face of the bell when the latter is lowered so as to continue the effect of the lowered bell in spreading the charge, said distributor also having surfaces inclined towards the center of the furnace.

2. A blast furnace having in combination a charging hopper, a bell closing upward 85 against said hopper, a distributing ring suspended in fixed position and in spaced relation below said bell and having a conical face constituting an annular enlargement of the face of the bell when the latter is lowered, and deflector plates interposed in the path of the charge from the bell to said ring to divert portions of the stream of the charge towards the center of the furnace.

3. A blast furnace having in combination a charging hopper, a bell closing upward against said hopper, a distributing ring suspended in fixed position and in spaced relation below said bell and having a conical face constituting an annular enlargement of the face of the bell when the latter is lowered, and deflector plates disposed in angularly spaced relation and in the path of the charge from the bell to said ring to divert portions of the stream of the charge toward 95 the center of the furnace, said deflector plates being detachably secured to the charging hopper support.

4. A blast furnace having in combination a receiving hopper, a charging hopper, small bells closing upwardly against the lower ends of said hoppers, an annular support at the top of the furnace and outlet of said charging hopper and a distributor suspended from said support, said distributor being in the form of a hollow truncated cone to distribute the stock outward and means for diverting some of the stock into the top opening of said cone.

5. A blast furnace having in combination 110 a charging hopper, a small bell closing upward against the lower end of said hopper, and an annular support disposed around said hopper, a distributor in the form of a hollow truncated cone supported from said support 115 having a sloping surface in substantial alignment with the outer surface of said bell when the latter is in its lowered position and deflectors disposed in angularly spaced relation between the bell and distributor and 120 125 130

adapted to divert a portion of the charge to the top opening of the distributor.

6. A blast furnace having in combination a charging hopper, a relatively small bell closing upward against the lower end of said hopper and a distributor suspended in fixed position below said bell and having a conical face constituting an annular enlargement of the face of the bell when the latter is lowered so as to continue the effect of the lowered bell in spreading the charge, said distributor also having surfaces inclined towards the center of the furnace, and means for diverting a portion of the charge to said last surfaces.

7. A blast furnace having in combination a charging hopper, a relatively small bell closing upward against the lower end of said hopper and a distributor suspended in fixed position below said bell and having a conical face constituting an annular enlargement of the face of the bell when the latter is lowered so as to continue the effect of the lowered bell in spreading the charge, and means for deflecting a part of said charge towards the center of the furnace.

8. A blast furnace having in combination a charging hopper, a relatively small bell closing upward against the lower end of said hopper and a distributor suspended in fixed position below said bell and having a conical face constituting an annular enlargement of the face of the bell when the latter is lowered so as to continue the effect of the lowered bell in spreading the charge, and means for deflecting a part of said charge towards the center of the furnace, said deflecting means being removable, so as to utilize in a particular case predetermined deflecting means.

9. A blast furnace having in combination a charging hopper, a relatively small bell closing upward against the lower end of said hopper and a distributor suspended in fixed position below said bell and having a conical face constituting an annular enlargement of the face of the bell when the latter is lowered so as to continue the effect of the lowered bell in spreading the charge, said distributor also having surfaces inclined towards the center of the furnace, and a series of means of different sizes for deflecting a predetermined part of said charge towards the center of the furnace, each one of said series being replaceable by the others of said series.

10. A blast furnace having in combination a charging hopper, a relatively small bell closing upward against the lower end of said hopper, a supporting ring carried by the top of said furnace, spaced brackets depending from said supporting ring and extending below said bell, a distributor fixed to the lower ends of said brackets, a cover plate extending between said supporting ring and said hopper, said cover plate having doors opposite said brackets, and deflecting means

removably fastened to said brackets, whereby a portion of said charge is diverted towards the center of the furnace.

11. A blast furnace having in combination a charging hopper, a relatively small bell closing upward against the lower end of said hopper, a supporting ring carried by the top of said furnace, spaced brackets depending from said supporting ring and extending below said bell, a distributor fixed to the lower ends of said brackets, a cover plate extending between said supporting ring and said hopper, said cover plate having doors opposite said brackets, and deflecting means removably fastened to said brackets, whereby a portion of said charge is diverted towards the center of the furnace, via inclined surfaces therefor on said distributor.

12. A blast furnace having in combination a charging hopper, a relatively small bell closing upward against the lower end of said hopper, a supporting ring carried by the top of said furnace, spaced brackets depending from said supporting ring and extending below said bell, a distributor fixed to the lower ends of said brackets, a cover plate extending between said supporting ring and said hopper, said cover plate having doors opposite said brackets, and deflecting means removably fastened to said brackets, whereby a portion of said charge is diverted towards the center of the furnace, via inclined surfaces therefor on said distributor, said deflecting means being removable through said doors and being replaceable by deflecting means of different size depending upon the amount of material desired to be diverted.

In testimony whereof, we have hereunto set our hands.
